LOADING DEVICE

Arthur Raymond Cunningham, Detroit, Mich.

Application November 4, 1946, Serial No. 707,658

11 Claims. (Cl. 214—78)

1

This invention relates generally to loading equipment for vehicles and refers more particularly to improvements in loading apparatus of the type used to transfer material such as manure from a pile into the body of a vehicle.

While the loading equipment forming the subject matter of this invention may be advantageously used to handle or load practically any material capable of being stored in a pile, it finds particular utility when employed for transferring manure from a pile directly into the body of a manure spreader.

One of the objects of this invention is to provide loading apparatus composed of a relatively few simple parts capable of being readily attached to conventional types of manure spreaders and also capable of expeditiously loading the body of the spreader from a pile of manure.

Another object of this invention is to provide loading apparatus having an element supported for rotation in opposite directions and having a fork operatively connected to the element by means responsive to initial rotation of the element in one direction to thrust the fork into a pile of material and responsive to continued rotation of the element in the same direction to swing the fork upwardly to a position above the body of the spreader where the material collected by the fork may be dumped into the body.

A further object of this invention is to provide loading apparatus of the above type wherein rotation of the element in the reverse direction swings the fork downwardly and, at the same time, shifts the fork in a direction to clear the pile of material to be loaded on the vehicle.

A still further object of this invention is to provide loading apparatus having guide means for the fork adapted to engage the top of the pile of material to be loaded for positioning the fork at the desired elevation relative to the pile and thereby determines to some extent the amount of material raised by the fork during any one cycle of operation.

The foregoing as well as other objects will be made more apparent as this description proceeds, especially when considered in connection with the accompanying drawings, wherein:

Figure 1 is a plan view of loading apparatus constructed in accordance with this invention and applied to a vehicle, such for example, as a manure spreader;

Figure 2 is a sectional view taken on the line 2—2 of Figure 1;

Figure 3 is an enlarged fragmentary elevational view showing the loading apparatus in different positions relative to the vehicle;

Figure 4 is a fragmentary perspective view of a part of the loading apparatus;

Figure 5 is a perspective view of a part of the apparatus shown in Figure 1;

Figures 6, 7 and 8 are respectively sectional views taken on the lines 6—6, 7—7 and 8—8 of Figure 2;

Figures 9 and 10 are respectively sectional views taken on the lines 9—9 and 10—10 of Figure 8; and

Figure 11 is a fragmentary elevational view similar to Figure 3, only showing the parts in a different position.

In the several figures of the drawings, the numeral 10 indicates loading apparatus constructed in accordance with this invention, and the numeral 11 designates one type of vehicle in connection with which the loading apparatus may be used. For the purpose of illustration, the vehicle shown is in the form of a conventional manure spreader having a body 12 open at the top and having ground engaging wheels 13 rotatably mounted on an axle 14 suitably supported at the rear end of the vehicle. The loading apparatus may be readily attached to conventional types of manure spreaders without appreciable alteration of the latter, and is adapted to be operated by the power take-off shaft of a standard tractor while the latter is hitched to the spreader.

In detail the loading apparatus comprises a pair of drums 15 respectively journaled on the axle 14 between the ground engaging wheels and sides of the body adjacent the latter wheels. The drums are rotated in opposite directions by suitable power take-off mechanism (not shown), forming a part of the standard equipment of orthodox tractors, through a power transmitting device 16. The device 16 comprises a casing 18 attachable to the front wall of the body and adapted to support a driven shaft 19 with its axis extending transversely of the body. The shaft 19 is driven in opposite directions by a drive shaft 20 extending through the front wall of the casing and having the front end portion fashioned for connection with the power take-off shaft of the tractor used to pull the vehicle. A bevelled gear is fixed to the rear end of the drive shaft 20 within the casing 18 and is adapted to alternatively mesh with a pair of bevelled gears 22 and 23. The bevelled gears 22 and 23 are respectively secured to a sleeve 24 at opposite sides of the drive gear 21 and the sleeve 24 is splined on the

drive shaft 19 for sliding movement in opposite directions relative to the drive shaft 19. As shown particularly in Figure 9 of the drawings, a pin 25 is secured to the drive shaft 19 and projects into an elongated slot 26 formed in the sleeve 24. The slot 26 is concealed by the hub 27 of the bevelled gear 22, and an annular groove 28 is formed in the hub 27 for receiving the furcations of a suitable shifting fork 29. The furcations of the fork 29 are respectively secured to opposite ends of a sleeve 30, and the latter in turn is secured to a shaft 31. The shaft 31 extends transversely through the casing 18 and is journaled in the opposite side walls thereof. A suitable handle 32 is secured to one end of the shaft exteriorly of the casing to enable swinging the shifting fork in opposite directions about the axis of the shaft 31. It will be noted that rocking movement of the shifting fork 29 in opposite directions reciprocates the sleeve 24 on the drive shaft 19 to alternatively mesh the bevelled gears 22 and 23 with the drive gear 21. Thus the driven shaft 19 may be selectively rotated in opposite directions by merely manipulating the handle 32.

The opposite ends of the shaft 19 project beyond the ends of the casing 18 and a pair of sprockets 33 are respectively secured to the projecting ends of the driven shaft. The sprockets 33 are respectively connected to the drums 15 by chains 34 and cables 35. The cables 35 are respectively wound around the drums 15 and the free ends thereof are secured to the corresponding ends of the chains 34. Thus the drums 15 are rotated by the driven shaft in the same direction of rotation as the latter.

Upon reference to Figures 1 to 3 inclusive of the drawings, it will be noted that a pair of arms 36 are located at opposite sides of each drum 15 and extend rearwardly from the latter. The front ends of the arms are pivoted to the adjacent drum 15 by means of a pin 37 and the rear ends of the arms at opposite sides of the vehicle are connected by a pick-up member such, for example, as a fork 38. The fork 38 comprises a rearwardly opening channel-shaped bar 39 having the opposite ends respectively secured to the arms 36 and having tines 40 secured thereto.

Located directly above the arms 36 at each side of the vehicle is a second pair of arms 41.

The front end portions of the arms 41 at each side of the vehicle are pivoted to opposite sides of the adjacent drum 15 by a pin 42, and the free ends of the innermost arms 41 at each side of the vehicle are bent inwardly to provide portions 43 adapted to seat on the top of a pile of material indicated in Figure 3 of the drawings by the numeral 44. The arms 36 and 41 at each side of the vehicle are connected by a link 45. The lower ends of the links are respectively pivoted to the arms 36 by pins 46, and the upper ends of the links are respectively pivoted to the arms 41 by pins 47.

The pins 37 and 42 are spaced radially outwardly from the axis of rotation of the drums 15, and are also spaced from each other circumferentially of the drums. The arrangement is such that rotation of the drums in the direction of the arrow A in Figures 2 and 3 of the drawings not only imparts an upward swinging movement to the arms 36 and 41, but also imparts a rearward shifting movement to the arms 36 and a forward shifting movement to the arms 41. On the other hand, rotation of the drum in the opposite direction indicated by the arrow B in Figures 2 and 3

of the drawings not only imparts a downward swinging movement to the arms 36 and 41, but in addition, shifts the arms 41 rearwardly, and the arms 36 forwardly.

With the above in view, reference is made to Figure 11 of the drawings wherein it will be noted that the rear end portions 43 on the arms 41 rest on the top of a pile of material 44 to be loaded into the body 12 of the vehicle. When the arms 41 are in the above position relative to the pile 44, the arms 36 are advanced to their forward-most positions, wherein the fork is located at the front side of the pile. Assuming now that the drums 15 are rotated in the direction of the arrow A, it will be noted that the fork 38 is thrust into the pile by rearward movement of the arms 36, and the end portions 43 are moved in a direction to disengage the same from the pile by the arms 41. Continued movement of the drums in the direction of the arrow A raises the material above the fork 38 and swings the material to the position indicated by the dot and dash lines shown in Figure 3 of the drawings. When the arms 36 and 41 are swung to their uppermost positions shown in Figure 3 of the drawings, the material supported by the fork is located directly above the body 12 of the vehicle, and is dumped into the body in a manner to be more fully hereinafter described. Assuming now that the drums 15 are rotated in their reverse direction indicated by the arrow B in Figures 2, 3 and 11 of the drawings, it will be noted that the end portions 43 of the arms are shifted rearwardly to again seat on the top of the pile and the fork 38 is shifted forwardly by the arms 41 so that the fork will clear the pile as it is swung to its lowermost position.

The material supported by the fork 38 is prevented from falling off of the fork during upward swinging movement of the latter, and this is accomplished by a baffle 48 extending between the arms 36 at opposite sides of the vehicle forwardly of the fork 38 and secured on a shaft 49 having the opposite ends respectively journaled on the arms 36. The baffle 48 is normally urged to its released position by means of a spring 50 coiled around the shaft 49 and having one end engaging the baffle in the manner shown in Figure 5 of the drawings. The opposite end of the spring 50 engages the bar 39 adjacent the shaft 49 and reacts against this bar to urge the baffle to its tipped position. The baffle is normally held against movement to its released or tripped position by a control lever 51 secured to a rock shaft 52 located at the front side of the vehicle body. The rock shaft 52 is journaled on a bracket 53, and a link 54 is secured to one end of the rock shaft in the manner clearly shown in Figure 4 of the drawings. The free end of the link 54 is connected to one end of a cable 55 having the opposite end connected to the forward end of a link 56. The rear end of the link 56 is connected to the shaft 49 and cooperates with the cable 55 and link 54 to hold the baffle 48 in its operative position against the action of the spring 50 until the rock shaft 52 is manipulated by the control 51. Rocking movement of the shaft 52 swings the link 54 downwardly to release the tension on the cable 55 sufficiently to permit the spring 50 to tip the baffle 48. This operation is, of course, effected after the material has been raised by the fork 38 to a position over the vehicle body 12.

In order to prevent any possibility of swinging movement of the fork 38 beyond its uppermost position shown by the dot and dash lines in Figure 3 of the drawings, the upper ends of the links

45 are latched to the guide arms 41 at opposite sides of the vehicle. For accomplishing this latching operation, a pair of latches 57 are respectively pivotally connected intermediate the ends to the arms 41 forwardly of the adjacent ends of the links 45. The lower ends of the latches are formed with weights 58, and the upper ends of the latches are provided with hooks 59. The purpose of the weights 58 at the lower ends of the latches is to normally hold the hook portions 59 out of engagement with the upper ends of the links 45 until the fork and guide arms 36 and 41, respectively, approach their uppermost positions shown by the dot and dash lines in Figure 3 of the drawings. When the arms are swung to their uppermost positions, the hook portions 59 on the latches hook over the adjacent ends of the links 45 and lock the arms 36 and 41 against further movement in an upward direction. When, on the other hand, the arms are swung downwardly, the hooked ends 59 of the latches 57 are released from the links 45 and permit the arms 36 and 41 to return to their initial starting positions shown in Figure 11 of the drawings. In this connection it will be noted that the upper ends of the links 45 are formed with a series of longitudinally spaced openings 60 for selectively engaging the pins 47 to vary the effective lengths of the links, or in other words, to vary the distance between the fork arms 36 and guide arms 41. Of course, varying the effective lengths of the links 45 changes the location of the upper ends of these links relative to the latch members 57 and necessitates adjusting the latch members along the guide arms 41. In order to accomplish this result the guide arms 41 are formed with a series of openings 61 spaced from each other lengthwise of the arms and adapted to selectively receive the pivots for the latch members 57.

What I claim as my invention is:

1. A loading device for a vehicle having an axle supporting ground engaging wheels and having a body, said device comprising an element supported on the axle for rotation relative to the ground engaging wheels, material handling means projecting from one end of the body, said means embodying a member responsive to rotation of the element in one direction to pierce a pile of material and responsive to continued rotation of the element in said one direction to swing the material over the top of the vehicle body.

2. A loading device for a vehicle having an axle supporting ground engaging wheels and having a body, said device comprising an element supported on the axle for rotation relative to the ground engaging wheels, material handling means projecting from one end of the body and having a pick up member, a connection between the member and element responsive to rotation of the element in one direction to thrust the pick-up member into a pile of material and responsive to continued rotation of the element in said one direction to swing the pick-up member to an elevated position directly over the body.

3. A loading device for a vehicle having an axle supporting ground engaging wheels and having a body, said device comprising an element supported on the axle for rotation relative to the ground engaging wheels, material handling means projecting from one end of the body and having a fork, a connection between the fork and element responsive to rotation of the element in one direction to thrust the fork into a pile of material and responsive to continued rotation of the element in said one direction to swing the

fork to an elevated position directly over the body, a baffle positioned to retain the material on the fork during swinging movement thereof, and means for tripping the baffle when the material is elevated to a position over the vehicle body to dump the material into the body.

4. A loading device for a vehicle having an axle supporting ground engaging wheels and having a body, said device comprising an element supported on the axle for rotation relative to the ground engaging wheels, means for rotating the element in one direction, material handling means projecting from one end of the body and having a fork, an elongated member having one end connected to the fork and having the opposite end pivoted to the rotatable element in a position whereby initial rotation of the element in said one direction thrusts the fork into an adjacent pile of material and continued rotation of the element in the same direction swings the fork to a position over the body of the vehicle, means for rotating the element in the opposite direction to retract the fork and return the latter to its lowermost position, and means for guiding movement of the fork in both directions of movement thereof.

5. A loading device for vehicles having a body, comprising an element supported for rotation, means for rotating the element in one direction, material handling means projecting from one end of the body and having a fork, an elongated member having one end connected to the fork and having the opposite end pivoted to the rotatable element in a position whereby initial rotation of the element in said one direction thrusts the fork into an adjacent pile of material and continued rotation of the element in the same direction swings the fork to a position over the body of the vehicle, guiding means for the fork including an elongated member located above the first member in a position to enable seating one end on the top of the pile and having the opposite end pivoted to the rotatable element, and a link having the opposite ends respectively pivotally connected to said members intermediate the ends thereof.

6. A loading device for vehicles having a body, comprising a rotatable element, material handling means projecting from one end of the body, said means including a fork, an arm having one end secured to the fork and having the opposite end pivoted to the element at a point spaced radially from the axis of rotation thereof, a guide arm located above the fork arm and positioned to enable seating the end thereof adjacent the fork on the top of a pile of material to be loaded in the body, means pivotally connecting the opposite end of the guide arm to said element at a point spaced radially outwardly from the axis of rotation of the element and spaced circumferentially of the element from the pivotal connection of the fork arm with the element, a link having the opposite ends respectively pivotally connected to the guide and fork arms intermediate the ends thereof, and means for rotating the element in opposite directions.

7. A loading device for vehicles having a body, comprising a rotatable element, material handling means projecting from one end of the body, said means including a fork, an arm having one end secured to the fork and having the opposite end pivoted to the element, a guide arm located above the fork arm and positioned to enable seating the end thereof adjacent the fork on the top of a pile of material to be loaded in the body,

means pivotally connecting the opposite end of the guide arm to the element, a link having the opposite ends respectively pivotally connected to the guide and fork arms intermediate the ends thereof, the pivotal connections between the arms and element being spaced radially outwardly from the axis of rotation of the element to enable both arms to swing in response to rotation of the element and also being predeterminedly spaced from each other to effect lengthwise movement of the arms in opposite directions upon rotation of the element in one direction, and means for selectively rotating the element in opposite directions.

8. A loading device for a vehicle having an axle supporting ground engaging wheels and having a body, said device comprising a pair of elements spaced from each other transversely of the vehicle and rotatable about the axle independently of the ground engaging wheels, material handling means projecting from one end of the body, said means including a fork positioned beyond the end aforesaid of the body and extending in the direction of the axis of rotation of the elements, a pair of arms having corresponding ends respectively connected to opposite ends of the fork and having the other ends respectively pivotally connected to the rotatable elements at points spaced radially outwardly from the axis of rotation of the elements, and a connection between the arms and elements responsive to initial rotation of the elements in one direction to thrust the fork into a pile of material and responsive to continued rotation of the elements to swing the fork to an elevated position over the body.

9. A loading device for vehicles having a body, comprising a pair of elements spaced from each other transversely of the vehicle and rotatable about a common axis, material handling means projecting from one end of the body, said means including a fork positioned beyond the end aforesaid of the body and extending in the direction of the axis of rotation of the elements, a pair of arms having corresponding ends respectively connected to opposite ends of the fork and having the other ends respectively pivotally connected to the rotatable elements at points spaced radially outwardly from the axis of rotation of the elements, a connection between the arms and rotatable elements for guiding movement of the fork in response to rotation of the elements, said guiding connection embodying a second pair of arms located above the fork arms and having corresponding end portions adapted to seat on a pile of material to be loaded in the body, means respectively pivotally connecting the opposite ends of the guide arms to the elements at points spaced radially from the axis of rotation of the elements and spaced circumferentially from the pivotal connections between the fork arms and elements, and links having the opposite ends respectively pivotally connected to the fork and guide arms intermediate the ends of the latter.

10. A loading device for vehicles having a body, comprising a pair of elements spaced from each

other transversely of the vehicle and rotatable about a common axis, material handling means projecting from one end of the body, said means including a fork positioned beyond the end aforesaid of the body and extending in the direction of the axis of rotation of the elements, a pair of arms having corresponding ends respectively connected to opposite ends of the fork and having the other ends respectively pivotally connected to the rotatable elements at points spaced radially outwardly from the axis of rotation of the elements, a connection between the arms and rotatable elements for guiding movement of the fork in response to rotation of the elements, said guiding connection embodying a second pair of arms located above the fork arms and having corresponding end portions adapted to seat on a pile of material to be loaded in the body, means respectively pivotally connecting the opposite ends of the guide arms to the elements at points spaced radially from the axis of rotation of the elements and spaced circumferentially from the pivotal connections between the fork arms and elements, a pair of links having the opposite ends respectively pivotally connected to the guide and fork arms intermediate the ends, means for rotating the elements in opposite directions, and means responsive to upward swinging movement of the arms by said elements to latch the links to the guide arms and responsive to downward swinging movement of the arms to release said latch means.

11. A loading device for vehicles having a body, comprising an element supported for rotation, means for rotating the element in one direction, material handling means projecting from one end of the body and having a fork, an elongated member having one end connected to the fork and having the opposite end pivoted to the rotatable element in a position whereby initial rotation of the element in said one direction thrusts the fork into an adjacent pile of material and continued rotation of the element in the same direction swings the fork to a position over the body of the vehicle, means for rotating the element in the opposite direction to retract the fork and return the latter to its lowermost position, and guiding means for the fork engageable with the top of the pile of material to be loaded for locating the fork at the proper elevation relative to the pile.
